HAIR DRESSING ACCESSORY

Filed Feb. 21, 1928

By his Attorney
John Gundstein

Inventor
Jacob Oppenheim

UNITED STATES PATENT OFFICE.

JESSE OPPENHEIM, OF NEW YORK, N. Y.

HAIRDRESSING ACCESSORY.

Application filed February 21, 1928. Serial No. 255,875.

This invention relates to hair dressing accessories for women, and is directed to a hair piece adapted to be applied over short hair regions of a bobbed head to give the appearance of a desired long hair coiffure.

One object of the invention is to provide improved hair pieces of the character described which shall be readily applied over desired regions of and easily conformed to the wearer's head, which shall be securely attached to comfortably fit in a set position, and which may be incorporated with the natural hair so as to be indistinguishable from the latter.

Another object of the invention is to provide in a hair piece of the character described, an improved attaching means including spaced helical spring coils for engaging with the natural hair to retain the hair piece in position.

20 A further object of the invention is to provide an improved hair piece of the character described comprising a simplified structure, which shall be relatively inexpensive to manufacture, convenient to apply or remove, 25 adapted to be incorporated in various styles of coiffure, and practical and efficient to a high degree in use.

Other objects of this invention will in part be obvious and in part hereinafter pointed out.

The invention accordingly consists in the features of construction, combinations of elements, and arrangement of parts which will be exemplified in the constructions hereinafter described, and of which the scope of application will be indicated in the following claims.

In the accompanying drawing, in which are shown various possible illustrative embodiments of this invention,

40 Fig. 1 is a rear view of a coiffure with an improved head dress piece embodying the invention in use;

Fig. 2 is a view of the rear side of the improved head dress piece showing in detail the spaced coil mounting attachments;

Fig. 3 is a fragmentary top view of the head dress piece shown in Figs. 1 and 2;

45 Figs. 4 and 5 are rear side views of modified construction of the improved head dress pieces; and

Figs. 6 and 7 are fragmentary top views of the head dress pieces shown in Figs. 4 and 5 respectively.

Referring in detail to the drawing, 10 denotes a coiffure with an improved head dress 55 embodying the invention in the form of a back piece 11. Said piece may comprise separate tufts, strands, or switches of hair secured together and adapted to be arranged after attaching to the wearer's head, or as shown 60 may comprise a continuous mass of hair 12 permanently dressed in puffs, curls, ringlets, or clusters.

The hair mass 12 is of the texture and color of the natural hair of the wearer, and may be 65 fabricated in any well understood manner, as for example constructed of a plurality of wefts 12^a of curled hair strands 12^b.

A narrow, textile, relatively non-extensible, ribbon member 13 is secured lengthwise 70 of said wefts 12^a on the rear side of the piece 11. Said member 13 may have each end terminated by a small ring fastener 14 and mounted inwardly of each of the ends there is a helical closely wound spring wire coil 15. 75 Eyelet ends 15^a are provided on said coils, one eyelet end of each coil being anchored to said member 13 by stitches 17 inwardly of a ring fastener. The other eyelet end of each coil has a looped strap 16 interconnecting it 80 with the adjacent ring fastening as is clearly shown in Figs. 2 and 3. The helical closely wound, spring coil 15 forms quick attachment means for engaging with natural short hair of the wearer, said means facilitating 85 mounting and removing the back piece, as will now be described.

To apply the improved head dress piece 11 over a region of natural short hair at the back of the head adjacent the neck, a looped 90 strap 16 is grasped in each hand and sufficient pulling force applied to stretch said coils, and to place the intermediate portion of the ribbon member 13 in tension. The coils are then pressed against the scalp of the region 95 to be covered by the hair piece 11. The natural short hair, of said region position themselves between the individual turns of the coils, and on releasing the stretching force, the short hair are firmly gripped by the coils. 100

By employing two coils 15 spaced widely apart with a flexible interconnecting ribbon member 13 in the attachment mounting for the hair dress piece 11, relatively large as well as small hair structures for covering a region 105 of the head may be readily, neatly and com-

fortably fitted and incorporated in a desired coiffure. An added advantage of the use of a plurality of such spaced coils is the practical elimination of possibility of wobbling 5 or shifting of the hair piece where a small single fastening member is employed.

Hair pins or other separate fastening means are not required since opposite extreme ends of the hair piece 11 secure the latter in place. 10 This attachment construction also leaves the mid-portions of the hair piece 11 flexible so that the latter may be readily conformed to the contour of the wearer's head. Using two coils 15 also permits making each coil of 15 relatively short length so that they may easily be concealed. Anchoring but one end of each coil to the member 13 as described above, also facilitates adjusting and positioning the hair piece since the free ends of said coils 20 carrying the loop straps are permitting limited movement. Thus the attachment construction embodying the invention supports the hair piece 11 in position unaccompanied by any discomfort such as experienced in 25 wearing a too rigid or loose coiffure.

In Figs. 4 and 6 a modified construction of the improved hair dress piece is shown comprising a back piece 111 which is similar in all respects to the hair piece 11 described above 30 with the exception that instead of fabricating the hair mass 112 in wefts, the curled hair strands 112^b are mounted on a ventilated lace base 112^a. The ribbon member 13, ring fasteners 14, coils 15 and loop straps 16 are disposed and secured on said base as in the construction of the hair piece 11.

A hair piece embodying the invention in the form of a puff 211 is shown in Figs. 5 and 7. Since the latter is relatively short, 40 the hair mass 212 may be mounted on a bendable member 213 comprising a wire reinforced ribbon secured to extend along the weft 212^a, the free ends 213 of said member being infolded and bendably adjustable within the puff structure.

The coils 215 are secured to extend beyond the bent ends 213^a of said member and the loop straps 216 are provided at the free ends of the coils 215. The member 213 serves the 50 same purpose and functions in the same manner with respect to the coils as do ribbon members 13 in the hair pieces 11 and 111.

The hair pieces 111 and 211 are applied and incorporated in the natural hair to form 55 a desired coiffure, and removed in a similar manner as that described above for the hair piece 11.

It will thus be seen that there is provided a device in which the several objects of this 60 invention are achieved, and which is well adapted to meet the conditions of practical use.

As various possible embodiments might be made of the above invention, and as various 65 changes might be made in the embodiment

above set forth, it is to be understood that all matter herein set forth or shown in the accompanying drawing is to be interpreted as illustrative and not in a limiting sense.

Having thus described my invention, I 70 claim as new and desire to secure by Letters Patent:—

1. A hair dress piece of the character described comprising a hair tuft, and an attachment means mounted thereon consisting 75 of a member attached to said tuft and a pair of spaced helical spring coils secured to said member adjacent the ends thereof for engaging with the natural hair of the wearer.

2. A hair dress piece of the character described 80 comprising hair adapted to cover short, natural hair regions of a coiffure, an attachment means secured to said hair consisting of a non-extensible member, a pair of spaced helical spring coils for engaging with 85 the natural hair of the wearer, each coil having an end secured to said member, and gripping means terminating the other ends of said coils.

3. A hair dress piece of the character described 90 comprising hair tufts mounted on an attachment means, said means including an elongated non-extensible wire reinforced ribbon on which said tufts are mounted, helical spring coils secured by one end of each to 95 the opposite end portions of said ribbon for engaging the natural hair of the wearer, and finger gripping means depending from the other ends of said coils.

4. A hair dress piece of the character described 100 comprising a hair structure and helical spring coils secured at spaced portions of said structure, the other ends of said coils having finger gripping means adapted to receive a pulling force for stretching said coils as and for the purpose described and specified.

5. In a hair dress piece of the character described, attachment means including a pair of helical spring coils, a member secured to an 105 end of each coil, the other ends of said coils having finger gripping means for applying a pulling force to stretch the coils and tension 110 for engaging said attachment means with the natural hair of the wearer.

6. A hair piece of the character described 115 comprising a hair tuft, and an attachment means mounted thereon consisting of a flexible member and a plurality of spaced helical spring coils secured only at their adjacent inner ends to said member, the outer ends of said springs being free to permit stretching said springs for engaging with the natural hair of the wearer.

7. In a hair piece of the character described 120 comprising a hair tuft, and an attachment means mounted thereon consisting of a flexible, non-extensible member and a plurality of helical spring coils, each of said coils being secured at one end only to said non-extensible member whereby said coils may be simultane- 125 130

ously stretched for engaging with the natural hair of the wearer.

8. In a hair piece of the character described, comprising a hair tuft and an attachment means mounted thereon consisting of a flexible, non-extensible member and a plurality of helical spring coils, each of said

coils being secured to said member at one end only and in spaced relation to each other whereby said coils may be simultaneously stretched for engaging with the natural hair of the wearer. 10

In testimony whereof I affix my signature.

JESSE OPPENHEIM.
